SIGNALING SYSTEM

George L. Usselman, Port Jefferson, N. Y., assignor to Radio Corporation of America, a corporation of Delaware

Application September 9, 1943, Serial No. 501,647

4 Claims. (Cl. 179—171.5)

In signaling systems comprising a wave source and wave modulating tubes associated therewith, it is desirable to have a constant voltage source of direct current supply in order that distortion of the modulated wave is not caused during operation due to poor voltage regulation.

In systems as described above, for operation on telephony or telegraphy signals the modulation tube load and operation is different for the two types of signals and the drain on the direct current source is different in each case, thereby increasing the need of a compensated or regulated source in order that distortion does not result due to poor regulation.

In systems where the wave source is to be modulated as to timing in accordance with telephony or telegraphy signals and the modulating tube or tubes are simulated reactances controlled in accordance with the signals by controlling the current therethrough distortion as such results from poor regulation in the direct current supply source, and in addition considerable undesired amplitude modulation may be caused along with the desired timing modulation.

The general object of my invention is improved operation of telephony or telegraphy systems using an unregulated or poorly regulated direct current supply source.

This general object is attained by loading the source with a thermionic load that is of different value for the two types of signals and varying the load as the signals vary in a direction to compensate changes in the load placed on the source by the modulator and wave source as modulation is carried out. By the expression modulation here is meant control by code or voice or similar signals.

Other objects, and the manner in which the same are attained, and the advantages which flow from the use of my invention will appear from the detailed description which follows. In this description reference will be made to the attached drawing in which the single figure illustrates one embodiment of a signaling system arranged in accordance with my invention.

In describing my improved means, I have shown the same incorporated in signaling systems as disclosed in my United States Patents No. 2,298,436, No. 2,298,437 and No. 2,298,438, all dated November 13, 1942. It will be understood, however, that the improvements apply equally well to signaling systems of other types wherein a wave source, which may be a tube generator or amplifier, is modulated by code or voice acting on the char-

acter of the wave through a modulator tube or tubes.

In the drawing V_1 is an oscillation generator of the regenerative type having its cathode and grids G_1 and G_2 , the latter acting as an anode, connected in a grounded anode Hartley type oscillator. The anode 10 is coupled to an output circuit not shown and coupled to the generation electrodes and circuit by the electron stream in the tube. The condenser C_0 improves the generator operation.

The generated oscillations produce a voltage drop across the resistance R_1 , which is also a leak resistance for the grid G_1 , and from this resistance R_1 voltage of the generated frequency is fed by condenser 26 to the grid 24 of the modulator tube V_2 . The anode 40 of modulator tube V_2 amplifies this voltage and the same is set up in circuit L_2 , C_3 , C_4 and fed by crystal 5 to the grid G_1 .

The phase of the voltage at 24 , is say the same as at G_1 and the voltage is reversed by tube V_2 . The tank circuit L_2 , C_3 is detuned slightly to further shift the phase of the amplified voltage about 90° plus or minus so that on the grid G_1 is developed a voltage that is the resultant of the two voltages, i. e., the generated voltage and the amplified voltage fed back by V_2 which at no modulation are about 90° displaced in phase.

Tube V_2 has its grid 24 modulated through resistance R_2 by code from source 50 when switch MS is at the right or by voice from transformer T when the switch MS is at the left. This modulates the amplitude of one of the phase displaced voltages fed to the grid G_1 and as a consequence modulates the phase of the resultant voltage on G_1 in accordance with signals. The voltage then fed back to grid 24 of tube V_2 is correspondingly shifted in phase and the effect is accumulative so that the generated oscillations are modulated in frequency in accordance with signals.

It is believed that the brief description given above is sufficient, since the operation of this part of the system is known in the art, having been described in detail in my United States patents mentioned above. Attention is directed to Fig. 4 of Patent No. 2,298,437.

The direct current source 60 has a negative terminal grounded, being thereby connected to the cathodes of tubes V_1 and V_2 , and has its positive terminal coupled to the screen grids and anodes of tubes V_1 and V_2 to supply direct current operating voltages. The current in tube V_2 is controlled for signaling purposes as described above and this places on supply source 60 a vari-

able drain, thereby resulting in voltage fluctuations and as a consequence distortion in the signals.

To insure a constant voltage at the source 80 which may be an unregulated supply source, I provide two compensation tubes V₃ and V₄. These two tubes have their cathodes 62 and 64 tied together and connected to ground through the cathode resistor 66 shunted by bypassing condenser 68. The switch 69 when in the left hand position connects the cathodes 62 and 64 directly to ground, thus shunting resistance 66.

The control grids 70 and 72 of the tubes V₃ and V₄ are connected by resistances R₈ and R₉ to the switch MS and by said switch in the left hand position through the secondary winding of transformer T and bias source 74 to ground. When the switch MS is at the right these grids are connected by the bias source 76 to ground.

The anode 80 and screen grid of tube V₃ is connected by resistance 82 and switch 69 in the left hand position to source 80. The anode 84 and screen grid of tube V₄ is connected by resistance 86 to the source 80.

When voice or similar modulation is to be used the switch MS is closed in the position shown as is the switch 69. The resistance 66 is thereby short-circuited and the cathodes of tubes V₂, V₃ and V₄ are connected directly to ground.

The grids 70 and 72 of tubes V₃ and V₄ are now connected by switch MS to one end of the secondary winding of transformer T, while the grid 24 of tube V₂ is connected to the other end of this winding. The anode circuit of tube V₃ is interrupted by switch 69 and thus the tube V₄ the anode 80 of which is connected to source 80 serves to load the said source differentially with respect to the loading thereof during operation by the modulator tube V₂. The connections including the bias resistance R₈ are such that a substantially constant drain and load is placed on source 80. During modulation tubes V₄ and V₃ are modulated by transformer T in phase opposition, that is in pushpull relation, so that when anode current increases in tube V₂ it decreases a like amount in tube V₄ and vice versa, thereby maintaining a constant load current and consequently constant load voltage is maintained.

In the code or telegraphy position switch MS is moved to the right and switch 69 is moved to the left. (The showing is schematic and these switches in practice may be arranged for common control as desired.) This removes the short circuit across resistance 66 and the cathodes of tubes V₂, V₃ and V₄ are biased positive with respect to ground by current through resistance 66.

The anodes of both tubes V₃ and V₄ are now connected to the source 80 by switch 69 and the grid of tube V₂ is connected to the keying means 58 by switch MS.

The tubes V₃ and V₄ now both operate as compensator tubes. During keying when the anode current of the modulator tube V₂ is increased by a decrease in negative bias on the control grid 24, the current in the common cathode resistor 66 is increased. This increases the negative bias on the grids 70 and 72 of the compensator tubes V₃ and V₄, since their normal fixed control grid bias from source 76 is unchanged, thereby reducing the anode current in the compensator tubes by almost the same amount that the current to the anode of tube V₂ has been increased. When the anode current in the modulator tube V₂ is decreased by keying its grid 24 more negative

the drop through resistance 66 decreases, the potential on the grids 70 and 72 of tubes V₃ and V₄ becomes less negative and these tubes take more current to compensate the decrease in current through tube V₂. Consequently, substantially constant rectifier (in say 60) load current and voltage is maintained without additional power supply regulation.

The grid bias on tubes V₂, V₃ and V₄ is not necessarily higher in the telegraph position as compared to the phone position although the cathode bias may be higher. The grid bias on these tubes can be made to have any desired value by adjustments of the bias sources 74, 76, and 78. The purpose of cathode resistor 66 is for a differential biasing means (opposite biasing means) for tubes V₃ and V₄ when tube V₂ is keyed by telegraph signals. The cathode resistor 66 is not needed for compensation in the telephone position. In fact, its use in this latter case causes distortion of the signal and sometimes undesirable uncontrolled oscillations in these circuits. Hence the switch 69 for shorting resistor 66 in the phone position. It might be stated here that bias sources 74, 76, and 78 are actually obtained from the same rectifier but through different potentiometers.

In the embodiment used for the phone setting one compensator, tube V₄, gives substantially perfect compensation, that is, constant voltage at the source and on the tube electrodes. In the telegraph setting two compensator tubes gives better compensation than one tube. Perfect compensation in the telegraph setting is not feasible by this method but also perfect compensation for the telegraphy setting is not necessary. However, the compensation obtained in my system is satisfactory.

I claim:

1. In apparatus of the class described, a source of direct current potential, a tube having electrodes in a direct current circuit including said source as a supply of operating potential, connections for controlling the current through said tube in accordance with telephony signals or code signals whereby said source is loaded variably during operation, a pair of compensating tubes each having output electrodes, a direct current circuit including said source for the output electrodes of one of said pair of tubes when telephony is used and both of said pair of tubes when code is used and connections for controlling the current through said one of said pair of tubes in a sense opposite to control of the current through said first tube by telephony and connections for controlling the current through both of said pair of tubes in a sense opposite to the control of the current through said first tube by code.

2. In apparatus of the class described, a modulator tube arranged to modulate wave energy in accordance with telephony or code signals, said modulator tube having electrodes including a cathode and an anode, a source of direct current in a direct current circuit for said cathode and anode, a pair of compensating tubes each having an anode and a cathode, connections for modulating the current through one of said compensating tubes in phase opposition with respect to control of said first tube by telephony signals, connections between the output electrodes of said one of said compensating tubes and said source of direct current, connections for controlling the current through both of said compensating tubes in phase opposition with respect to the control of said first tube by code, and connections be-

tween the output electrodes of both compensating tubes and said source of direct current.

3. In a signaling system, a modulator tube having electrodes including an anode and cathode, a source of direct current having a positive terminal connected to said anode and a negative terminal grounded, a bias resistance connecting the cathode of said tube to ground, a source of telephony signals, a source of telegraphy signals, connections including a switch connecting one or the other of said signal sources to an electrode of said tube to control the current therethrough, a pair of compensator tubes each having output electrodes, connections including a switch connecting the output electrodes of one of said compensator tubes in series with said source of direct current and a phase reversing means connecting an electrode in said one compensating tube to said source of telephony signals when said one electrode in said modulator tube is connected to said source of telephony signals, and other connections connecting the output electrodes of both of said compensating tubes in series with said direct current source through said bias re-

sistance and connecting an electrode in each of said compensating tubes to said source of telegraphy signals when the same is connected to said one electrode in said modulator tube.

5. In a signaling system, a source of direct current potential, a tube having electrodes in a direct current circuit including said source as a supply of operating potential, connections for controlling the current through said tube in accordance with telephony signals or code signals whereby said source is loaded variably during operation, a plurality of discharge devices each having electrodes, a direct current circuit, including said source, for the electrodes of at least one of said devices when telephony is used and for at least two of said devices when code is used and connections for controlling the current through said one of said devices in a sense opposite to control of the current through said first tube by telephony and connections for controlling the current through said two of said devices in a sense opposite to the control of the current through said first tube by code.
